UNITED STATES PATENT OFFICE.

THOMAS CRAETREE, OF WORCESTER, MASSACHUSETTS.

BOTTLE-SEALING DEVICE.

Application filed September 3, 1921. Serial No. 498,824.

To all whom it may concern:

Be it known that I, THOMAS CRABTREE, a citizen of the United States, residing at Worcester, in the county of Worcester and State of Massachusetts, have invented a new and useful Bottle-Sealing Device, of which the following is a specification.

This invention relates to a device for sealing bottles and jars containing root beer or any carbonated beverage or any liquid that may generate gas and cause pressure to be exerted on the sealing means.

At the present time the usual ways of temporarily sealing bottles that are put up in the home is to apply the so-called crown seal or some equivalent thereof with the use of mechanism which results in breaking a large per cent of bottles, or else the application of a cork together with a wire or the like for holding it down which is uncertain and consumes a great deal of time. In canning by the cold pack method, the jars are sealed by the use of a lever which necessitates reaching down into boiling water.

The principal object of this invention is to provide a device which can be applied to a bottle or jar very easily without the use of any complicated mechanism and therefore without endangering the breakage of the bottle, and at the same time provide it in such form that it will be so inexpensive that it can be used practically for this purpose while a single device is also capable of use over and over again. Another object of the invention is to provide a device which can be used for sealing canning jars, operating under the cold pack system, in such a way as to avoid the necessity of reaching down into the hot water, even for an instant.

Reference is to be had to the accompanying drawings, in which—

Fig. 1 is a central vertical sectional view of a preferred form of the invention shown in sealing position;

Fig. 2 is a side view of the same, and

Fig. 3 is a plan.

In the form illustrated, the invention is applied to a sealing element in the form of a cap 10 having a rubber or other soft covering 11 which is designed to rest on the top of the bottle or jar. It has to be pressed against it with sufficient force to prevent the entrance of air or the escape of gas. This cap 10 is provided with a

swivel socket 12 for receiving the swivel end of an operating screw 13. This screw has a thumb nut 14 integrally or otherwise fixedly secured to it. The screw fits in a nut 15 which has a conical exterior surface preferably.

For holding the device on the bottle or jar I provide a pair of levers 20. These are shown as formed of sheet metal and they have jaws 21 at the bottom adapted to engage under the top bead of the bottle or jar and located diametrically opposite each other. These sheet metal levers and jaws almost surround the top of the bottle in the form shown. They are provided with ears 22 projecting toward each other and diametrically opposite. Each pair of ears is connected by a pivot stud 23, these two pivot studs being in alignment with each other diametrically.

It is to be noted that the levers 20 slant inwardly toward the top so that they fit the conical surface of the nut 15 which they engage. It is to be observed also that the whole device consists of two units, first that one composed of the parts 11, 13 and 15, and second, that composed of the lever 20, and of course, connected parts. These two units are mounted independently of each other so that the device can be made to fit bottles and jaws of different sizes and shapes without any adjustment except the location of the nut 15 in proper place along the screw. There is no positive connection of the levers 20 with the screw 13 and its connected parts.

In the operation of the device the screw and nut are placed inside the levers with the nut raised as far as may be considered necessary. Then the whole device is placed over the top of the bottle or jar and the jaws 21 of the levers placed under the bead as indicated in the drawings. Now, the screw is turned down to force the cap, or its covering, into firm contact with the top of the bottle or jar. On account of the friction of the nut 15 on the concave surfaces of the upper ends of the levers 20 the nut is prevented from turning but the rotation of the screw has the effect of forcing the cap 10 and the nut 15 apart. This obviously forces the cap into intimate contact with the top of the jar or bottle and forces the nut outwardly or upwardly. This has the effect of forcing the levers 20 outwardly at the top and forcing the jaws 21 in at the bottom. This effectively holds all parts in po-

sition and yet when it is desired to open a bottle or jar it can be done simply by turning the screw to the left.

It will be seen further that the generation 5 of any pressure inside the bottle or jar will simply tend to force the jaws 21 more firmly into engagement with its top and thus there is no chance of the pressure resulting in the blowing off of the whole device. There is 10 also no danger of breaking the bottle because the jaws 21 where the pressure is applied extend almost all the way around it and pressure is not exerted at any one point or even at the two opposite points, while the 15 pressure of the cap 10 on the top of the bottle is exerted in the direction of its length where it is the strongest. The device is easily applied and can be used for sealing bottles and for canning purposes and it is 20 especially adapted for those uses in which it is not to be retained on the bottle or jar for any great length of time. It can be used over and over and does not require the employment of any external mechanical device. 25

Although I have illustrated and described only a single form of the invention, I am aware of the fact that modifications can be made therein by any person skilled in the 30 art without departing from the scope of the invention as expressed in the claims.

Therefore, I do not wish to be limited to all the details of construction or to the particular type of receptacle to which I have 35 shown it applied, but what I do claim is:—

1. In a device for sealing bottles and jars, the combination of a cap adapted to rest on the top of the receptacle to which it is ap-

plied, a screw swiveled to the cap for holding it down, a conical nut on the screw having its large end down and arranged to be moved up by the turning of the screw to hold the cap down, and a pair of levers pivoted together and located on opposite sides of the screw, said levers having concave upwardly extending converging arms adapted to engage the nut, and oppositely located concave jaws at their opposite ends adapted to engage under the bead of the receptacle to which it is applied, whereby when the nut is forced upwardly by the screw the jaws on the levers will be forced inwardly. 40 45 50

2. In a device for sealing bottles, jars or the like, the combination of a flat cap adapted to rest on the top of the receptacle, a screw extending upwardly therefrom and swiveled thereto, a nut on the screw adapted to be raised by turning the screw in a direction to force the cap down on the receptacle, a pair of levers independent of said screw 55 cap and nut but substantially surrounding them and having converging upwardly extending arms engaging the outer surface of the nut, whereby the raising of the nut will force said arms outwardly at the top, said levers having jaws at the bottom for engaging the neck of the receptacle and being pivoted together at a point between the jaws and converging arms, whereby the lowering 60 of the cap and the raising of the nut will 65 force said jaws together to grip the outside of the receptacle. 70

In testimony whereof I have hereunto affixed my signature.

THOMAS CRABTREE.
